of said cap and sufficient in size to receive the holding finger of a capping tool, for the purpose set forth.

2. In a bottle seal, a cap having a crimped skirt and an integral thumb piece with an opening therethrough terminating at the bottom of the skirt whereby said cap is provided with a free crimped portion above said opening, for the purpose set forth.

3. The herein described bottle seal comprising a cap and gasket, said cap having an integral thumb piece connected therewith at two points whereby an opening is formed between said connecting points with a por-

tion of the edge of the skirt of the cap 15 forming one wall thereof, said opening being sufficient in size to receive a holding finger of a capping tool, the portions connecting said thumb piece and cap being ribbed whereby the requisite stiffness is obtained with a maximum amount of the edge 20 of said skirt exposed.
